UNITED STATES PATENT OFFICE.

SCOTT J. BEACH AND SARAH A. BEACH, OF NORFOLK, CONNECTICUT.

COMBINED FOLDING CHAIR AND BATH-TUB.

SPECIFICATION forming part of Letters Patent No. 308,456, dated November 25, 1884.

Application filed October 4, 1883. (Model.)

To all whom it may concern:

Be it known that we, SCOTT J. BEACH and SARAH A. BEACH, of Norfolk, in the county of Litchfield and State of Connecticut, have invented a new and Improved Combined Folding Chair and Bath-Tub; of which the following is a full, clear, and exact description.

The object of our invention is to provide a new and improved combined folding chair and bath-tub which can be adjusted for use as a folding chair, or as a large or small bath-tub, or as a cot.

The invention consists in various parts and details and combinations of the same, as will be fully described and set forth hereinafter.

Reference is to be had to the accompanying drawings, forming a part of this specification, in which similar letters of reference indicate corresponding parts in all the figures.

Figure 1 is a perspective view of our improved combined chair and bath-tub, showing it adjusted for use as a chair. Fig. 2 is a front view of the same. Fig. 3 is a detail perspective view of the socket-plate for receiving the keys on the upper ends of the legs. Fig. 4 is a face view of a socket-plate, showing the key in place. Fig. 5 is a plan view of the underside of the folding chair, showing it extended and adjusted to be used as a frame for a bath-tub, parts being broken away. Fig. 6 is a longitudinal sectional elevation of a bath-tub constructed out of the folding chair, the section shown being on the line $x-x$, Fig. 5. Fig. 7 is a longitudinal sectional elevation of a smaller bath-tub. Fig. 8 is a cross-sectional elevation of the side bars of the chair on the line $y-y$, Fig. 5. Fig. 9 is a detail sectional plan view of part of the back-rest.

The chair-seat A, which can be made of fabric, leather, cane, perforated board, or any other suitable material, is secured to the side bars B.

On the inner edge of each side bar B a short dovetailed tongue, B², is secured, which projects into a longitudinal groove, C', in the outer surface of a corresponding sliding side bar C. The side bars C are united by a covering, A', made of leather or fabric, and adapted to slide under the seat-covering A.

On the inner end of each side bar C a short beveled tongue, C², is formed, which passes into a longitudinal groove, B', of the corre-

sponding outer side bar, B. The back-rest side bars D are hinged at their lower ends to the inner ends of the seat side bars B, and the said back-rest side bars D are each provided in their inner surfaces with a longitudinal groove, D'. The side bars E of the back-rest extension rest against the inner surfaces of the back-rest side bars D, and are provided in their inner surfaces adjoining the inner surface of the side bars D with longitudinal grooves E'.

On the upper end of each side bar D a short tongue, D², is formed, which projects into the corresponding groove, E', and on the lower end of each side bar E a tongue, E², is formed, which projects into the corresponding groove, D'.

To the outer surface of each back-rest side bar D a brace, F, is pivoted a short distance above the lower end, which brace has its lower edge notched at the free end, which notched free end of the brace moves in a staple, G, projecting from the outer surface of the corresponding side bar, B, in which staple the notched edge of the brace F can catch, and thus hold the back-rest at the desired inclination. The side bars E of the back-rest extension are provided in the inner surface and at the upper ends with short dovetailed grooves adapted to receive the dovetailed ends of a curved top cross-piece, G', which holds the upper ends of the side bars E of the back-rest extension in the proper position. The back-rest side bars D are united by fabric, leather, or other material, A², and the sliding back-rest bars E are also united by a piece of fabric or leather, A³, adapted to slide under the covering A² of the back-rest side bars D.

To the inner end of each sliding side bar C a short bar, H, is hinged in such a manner that it can swing against the bottom edge of the bar C. The bar C is provided with a spring-latch, H', adapted to catch on a stud, H², projecting from the hinged bar H, for locking the said hinged bar H in position in line with the bar C, as shown in Figs. 5 and 6.

On the inner surfaces of the ends of the sliding extension seat side bars C, on the inner surfaces of the free ends of the hinged bars H, and on the inner surfaces of the upper ends of the back-rest extension side bars E, socket-plates I are secured, which consist of

a plate provided with two ridges, I', inclined toward each other laterally and from the bottom to the top, so that they form a dovetailed mortise which is larger at the lower end than at the upper end. The said plates I are of cast metal, and are provided in the outer edge of one of the ridges I' with a notch, I². The chair is provided with three pairs of legs, J, pivoted to each other.

10 To the upper end of each leg a plate K is fastened in such a manner that it projects beyond the end of the leg, and on the outer end edge of the said plate K a dovetailed wedge-shaped tenon, L, is formed, which fits into the 15 socket formed by the ridges I' on the plate I.

To the outer side of the plate K a spring-strip, M, is fastened, the free end of which is opposite a notch, L', formed in the inner edge of the tenon L on one side of the plate K, 20 which notch is so arranged that when the tenon is in the mortise or socket formed by the ridges I' the said notch will correspond in position to the notch I² of the ridge I'. The outer surface of the spring M is beveled at the free end, 25 so that when the dovetailed tenon L is pressed into the socket formed by the ridges I' and the lower end of one of the ridges I' strikes the free end of the spring M it presses the said spring inward into the notch L', and when 30 the tenon is in the socket or mortise the free end of the spring M snaps outward and into the notch I² and prevents withdrawing the tenon from the mortise or socket. If the leg is to be removed, the free end of the spring M 35 must be pressed into the notch L' to disengage the said spring from the ridge.

The bath-tub is formed of a sheet or sack, S, made of strong rubber or other water-proof fabric, which is provided at the corner and on 40 the longitudinal sides with loops T.

The combined bath and chair is adjusted in the following manner: If it is to be used as a chair, the ends of one pair of legs are passed into the sockets at the outer ends of the bars 45 C, and then the ends of another pair of legs are passed into the sockets at the free ends of the hinged bars H, the bars H being swung down and locked, and the sliding bars C being pushed back to such an extent that the 50 hinged bars H will project beyond the rear ends of the side bars B. The back-rest is inclined to the desired position, and is held in this position by engaging the teeth of the bars F with the staples G. The cross-piece 55 G' is passed into the upper ends of the sliding side bars E of the back-rest, and the back-rest is lengthened as much as may be desired. The seat can be lengthened more or less. It will be observed that the seat is supported at 60 its front and rear ends, and that the joint of the back-rest will be somewhat in advance of the rear support of the seat.

If the device is to be used as a cot, the hinged bars H are swung down and locked in 65 position by the spring-hook H' and stud H², and the sliding bars C are drawn outward un-

til the short tongues C² strike against the inner ends of the tongues B², formed on the outer ends of the seat side bars B. The sliding bars E of the back-rest are withdrawn until their 70 short tongues E² strike against the tongues D² of the back-rest side bars D. The legs are then fastened in place, one pair at the outer ends of the sliding bars E, one pair at the free ends of the bars H, and one pair at the outer 75 ends of the sliding bars C. A mattress, &c., can then be placed on the coverings A, A', A², and A³.

If the device is to be adjusted for use as a bath-tub, it is inverted, so that the coverings 80 A, A', A², A³ rest on the floor, as shown in Figs. 5 and 6. The water-proof sack or sheet S is then suspended from the ends of the legs by means of the loops T, and water is poured into the pockets formed as shown in Fig. 6. 85

If the device is to be adjusted to form a child's bath-tub, the hinged bars H are swung against the under side of the sliding bars C. The sliding bars C and E are pushed inward, so that the length of the frame will 90 be equal to the combined lengths of the bars B and D, as shown in Fig. 7. One pair of legs J is held on the outer ends of the sliding bars C, and another pair is held on the outer ends of the sliding bars E, and a small sheet or 95 sack, S, is suspended from the upper ends of the legs, as shown.

The above-described apparatus can thus be adjusted for use as a large or small chair, a large or small cot, or a large or small bath-tub, and if the legs J on the hinged bars H are removed a single large bath-tub will be formed. 100

Having thus described our invention, we claim as new and desire to secure by Letters 105 Patent—

1. In a folding chair, the combination, with the seat side bars, said bars having rear hinged bars provided with legs, and the hinged back-rest side bars, of the seat extension-bars provided with legs, the back-rest extension-bars, and coverings for the aforesaid bars, substantially as shown and described, and for the purpose set forth. 110

2. In a folding chair, the combination, with the seat side bars B, the back-rest side bars D, and the coverings A and A², of the sliding seat side bars C, the sliding back-rest side bars E, the coverings A' and A³, secured to the sliding side bars C and E, respectively, and 120 the legs J, substantially as herein shown and described.

3. In a folding chair, the combination, with the seat - bars, sliding extension side bars hinged to the inner or rear ends, of the extension side bars, and of detachable legs connected to the front ends of the sliding side bars and to the free ends of the hinged bars, substantially as herein shown and described. 125

4. The combination, with the seat side bars B and the extension seat side bars C, of the bars H, hinged to the inner ends of the slid-

ing bars C, and provided with legs, the spring-latches H', the sockets secured to said hinged bars and to the extension seat side bars, and the supporting-legs J, fitted into said sockets, 5 substantially as herein shown and described.

5. The combination, with a seat-frame having an extension, and a hinged back-rest having an extension, of the legs for the support of the seat-frame and the back-rest extension, 10 and a water-proof sheet or sack for suspension from the free ends of the legs of the chair, the chair being placed in an inverted position, thereby forming a bath-tub, substantially as herein shown and described.

15 6. The side bar having the dovetailed socket or mortise, with the front edge of one side provided with a recess or notch, in combination with the leg having a dovetailed tenon provided with a recess, and a bevel-ended 20 spring-plate fitting at its outwardly-bent free end into the notch of the socket and retractible into the recess of the tenon, substantially as and for the purpose set forth.

7. The side bar having the dovetailed sock-

et or mortise II', provided on its front edge 25 with a notch or recess, I², in combination with the leg J, the plate K, provided at its free end with a dovetailed wedge-shaped tenon, L, having a notch, L', and of the spring M, secured to the plate K, substantially as herein shown 30 and described.

8. The side bar provided with ridges, one of which ridges is provided on its face with a notch, said ridges being inclined laterally toward each other and from the bottom to the 35 top, forming a dovetailed groove larger at the bottom than at the top, in combination with the leg having a tenon provided with a notch and coincidentally shaped with the said groove, and the bevel-ended spring-plate applied to 40 said leg, substantially as and for the purpose set forth.
